UNITED STATES PATENT OFFICE.

CHARLES L. GOODRUM, OF NEW YORK, N. Y., ASSIGNEE, BY MESNE ASSIGNMENTS, TO
WESTERN ELECTRIC COMPANY, INCORPORATED, A CORPORATION OF NEW YORK.

AUTOMATIC TELEPHONE SYSTEM.

1,216,305.

Specification of Letters Patent. Patented Feb. 20, 1917.

Application filed May 10, 1915. Serial No. 27,052.

To all whom it may concern:

Be it known that I, CHARLES L. GOODRUM, a citizen of the United States, residing at New York, in the county of New York and State of New York, have invented certain new and useful Improvements in Automatic Telephone Systems, of which the following is a full, clear, concise, and exact description.

10 This invention relates to telephone exchange systems employing machine switching, and particularly to systems or exchanges consisting of a number of offices. In trunking between offices in such exchanges it is the practice to relay or repeat the impulses for setting the selectors at the distant office from the incoming office to the distant office.

20 Due to the conductive separation of the trunk circuit at the repeater by condensers, it is necessary to provide means for preventing such condensers from changing the character of the impulses relayed to the distant office to set the selectors thereat, which 25 they would otherwise do in discharging.

Repeaters have been employed wherein 30 relays disconnect the condensers from the trunk while the impulses are being transmitted. After the selectors at the distant office have been set, these relays again connect the condensers to the trunk to complete the talking circuit.

This invention provides a highly efficient 35 repeater circuit wherein the use of such relays, or their equivalents, is rendered unnecessary and consists in inductively uniting the incoming line with the outgoing trunk by a low capacity repeating coil, and including in circuit with the repeater windings on the incoming side a relay which is 40 adapted to be operated by the sender in accordance with the digits of the wanted number to actuate a contact in circuit with the repeater windings in the trunk or outgoing side to produce impulses therein for 45 setting the selectors at the distant office.

The invention will be more readily understood when described by reference to the accompanying drawing which illustrates 50 only so much of a telephone system as is

necessary for a comprehension of the invention.

The calling subscriber at substation A upon removing his receiver would set in motion a line finder whose brushes 1, 2 only are shown, since such switches are well known in the art. The calling subscriber is thus connected to a first selector which is then set by the sender 5 operated by the calling subscriber in the well-known manner to step the brushes 3, 4 of the first selector 65 in operative relation to a row of trunks terminating in the office containing the wanted line. The first selector would then in the well-known manner automatically pick out an idle one of these trunks. The 70 operation of the apparatus up to this point is well known and therefore need not be described. It may be of the type shown in U. S. Patent 1,118,910.

When the idle trunk is found, the relay 75 6 thereof is energized by a circuit leading to the substation A as follows: free pole of the battery, left-hand winding of relay 6, conductor 7, winding 8 of the repeating coil 9, conductor 10, contact 11 of the first selector, brush 4 thereof, conductor 12, brush 2 of the finder, contact 13 thereof, line conductor 14, primary winding 15 of the induction coil at substation A, contact 16 and switchhook 17, transmitter 18, conductor 19, 85 sender 5, finder contact 20, finder brush 1, conductor 21, first selector brush 3, contact 22, conductor 23, winding 24 of repeating coil 9, conductor 25, right-hand winding of relay 6, to ground. The relay 6 at its left-hand front contact closes a circuit for a slow relay 26, which opens the circuit of release magnet 27 at the first selector. Relay 6 at its right-hand armature and front contact closes the trunk circuit leading to the distant office as follows: free pole of the battery, left-hand winding of relay 28 of the connector at the distant office, conductors 29, 30, winding 31 of repeating coil 9, conductor 32, right-hand armature and front 90 contact of relay 6, conductor 33, winding 34 of repeating coil 9, conductors 35 and 36, right-hand winding of relay 28 at the connector, to ground. The subscriber at sub-

station 2 now operates his dial 5 in accordance with the tens digit of the number of the wanted line. Each time the circuit of relay 6, above traced, is interrupted by the sender 5, the relay 6 is deenergized and interrupts at its right-hand armature and front contact the circuit traced for relay 28 at the connector. The armature of this relay in vibrating operates the primary magnet net of the connector, which magnet elevates the brushes 40, 49 to the level containing the terminals of the wanted line in the well-known manner. At the end of this series of interruptions, when the sender completely 10 restores and maintains the line relay 6 energized, the continued energization of the relay 28 at the connector will cause the change-over operation to take place at the connector to shift the circuit leading from the 15 contact of the relay 28 from operative relation to the primary magnet of the connector and into operative relation with the secondary magnet thereof. The subscriber at substation A now operates his dial 5 in accordance with the units digit of the number of the wanted line, whereupon the circuit of relay 6 is again intermittently interrupted, which in turn intermittently interrupts the circuit of relay 28 at the connector 20 which transmits impulses to the secondary magnet thereat to step the connector brushes 40, 49 to the terminals of the wanted line, whereupon the line is tested and if idle, ringing current is sent thereover, or if busy, 25 a busy signal is sent back to the calling subscriber. The apparatus for accomplishing these functions may be similar to that shown in the patent mentioned.

When the subscriber at substation B 30 moves his receiver, in response to the ringing current, the following circuit is closed to supply him with talking current: free pole of the battery, left-hand winding of relay 37, conductors 38, 39, connector brush 40, terminal 41, conductor 42, transmitter 43, switchhook 44, conductor 45, primary winding 46 of the induction coil, conductor 47, terminal 48, connector brush 49, conductors 50, 51, right-hand winding of 45 relay 37, conductor 52, to ground. The direct current which is supplied to the calling subscriber at substation B is prevented from flowing over the trunk conductors 30, 35 by condensers 53, 54 at the connector.

55 When the calling subscriber at substation A restores his receiver, he interrupts at switchhook 17 and contact 16 of the substation apparatus, the circuit of relay 6. This relay allows its armatures to fall back. 60 The left-hand armature in falling back causes the deenergization of the slow relay 26, which completes the circuit of release magnet 27 of the first selector over the fol-

lowing circuit: free pole of the battery, release magnet 27 of the selector, conductor 55, brush 56 of the selector, test contact 57, conductor 58, armature and back contact of slow relay 26, conductor 59, left-hand armature and back contact of relay 6 to ground. The right-hand armature of the relay 6, in falling back, causes the deenergization of relay 28 at the connector, which at its armature and back contact may close the connector release circuit to restore the connector. The apparatus is now restored and ready to be used in establishing another connection.

What is claimed is:

1. In a telephone exchange system, the combination with a pair of line conductors, a connecting circuit in sections, a repeating coil uniting said sections inductively, and means for connecting said line conductors with said connecting circuit, of a stepping relay, a metallic circuit including said line conductors, said relay and the repeater windings in the incoming section of said connecting circuit, said relay having a contact included in the outgoing section of said connecting circuit, means for operating said relay in accordance with the digits of the called number, and automatic switches adapted to be set by the impulses so produced.

2. In a telephone exchange system, the combination with a pair of line conductors, a connecting circuit in sections, a repeating coil uniting said sections inductively, and means for connecting said line conductors with said connecting circuit, of a stepping relay, a metallic circuit including said line conductors, said relay and the repeater windings in the incoming section of said connecting circuit, said relay having a contact controlling the continuity of the outgoing section of said connecting circuit, a sender adapted to interrupt said metallic circuit and thus operate said relay, and automatic switches adapted to be set by the impulses so produced.

3. In a telephone exchange system, the combination with a talking circuit divided into sections, a repeating coil uniting said sections inductively, of a relay bridged across the middle point of one side of said repeating coil and having a contact controlling the continuity of the other section, means for operating said relay in accordance with the digits of the called number, and automatic switches adapted to be set by the impulses so produced.

4. In a telephone exchange system, the combination with a pair of line conductors, a connecting circuit in sections, means for inductively uniting said sections including feed coils and a source of current, of a step-

ping relay, a metallic circuit including said line conductors, said relay and the feed coil windings in the incoming section of said connecting circuit, said relay having a contact included in the outgoing section of said connecting circuit, means for operating said relay in accordance with the digits of the

called number, and automatic switches adapted to be set by the impulses so produced.

In witness whereof, I hereunto subscribe my name this 8th day of May, A. D., 1915.

CHARLES L. GOODRUM.
